UNITED STATES PATENT OFFICE.

CHARLES P. KIMMEL, OF GARY, INDIANA.

RAIL-HOLDING CLAMP.

Application filed October 17, 1925. Serial No. 63,068.

To all whom it may concern:

Be it known that I, CHARLES P. KIMMEL, a citizen of the United States, residing at Gary, in the county of Lake and State of Indiana, have invented certain new and useful Improvements in a Rail-Holding Clamp, of which the following is a specification.

My invention relates to rail holding devices, and particularly to a novel clamp adapted for use in connection with a tie such as disclosed in the copending application of McManus & Kimmel, Serial No. 23,192, filed April 15, 1925, Patent No. 1,560,069, of Nov. 3, 1925.

An object of my invention is to provide holding means adapted for use in connection with metal ties, said means providing a positive, certain and unyielding hold for the rail. The parts are so designed that lateral or vertical thrusts or the components of such force are resisted by positive means as distinguished from means such as bolts and nuts. The thrusts mentioned are resisted in such manner that there is no escape or loosening of the rail without actual bending or distortion of the metal constituting the holding means.

The invention will be more readily understood by reference to the accompanying drawing, in which;

Fig. 1 is a plan view of holding means constructed in accordance with my invention.

Fig. 2 is a longitudinal sectional view therethrough;

Fig. 3 is a transverse sectional view therethrough;

Fig. 4 is an end elevation of the clamp.

Fig. 5 is a plan view thereof.

Fig. 6 is an end elevation of the resilient wedge;

Fig. 7 is a plan view thereof;

Fig. 8 is a side elevation of the retainer, and

Fig. 9 is an edge view thereof.

In the drawings, it will be seen that the device of my invention has been adapted for use in connection with a hollow tie, 10, such as described in my copending application, heretofore identified, and provided with a longitudinal slot, 11, in its upper surface. At a point adjacent to the location of the rail, 12, the slot, 11 is notched, at each side, as at 13.

The construction described may be duplicated on both sides of the rail or a permanent fastening device or abutment may be utilized at one side of the rail if desired. While I have shown the clamping means in duplicate, I will describe but one combination of parts.

It will be noted, however, that in Fig. 2, I have illustrated the fastening key or wedge in its final position at the right hand side, and in its initial position, before being driven into position, at the left hand side.

The holding device comprises a clamp having a bifurcated body portion, 14, a head, 15, adapted to overlie the base of a rail, 12, and a toe, 16, at the extremity of each of the bifurcations, 14. The lower portions of the toes are adapted to enter the notches, 13 and to abut against the rear walls thereof, while the upper portions of the toes provide stops, 17, for the wedge key about to be described. It will be noted that the clamp when positioned as shown, provides a positive thrust member against lateral movement of the rail base, the thrust being exerted directly against the metal of the tie.

The retainer shown in detail in Figs. 8 and 9, is of generally I-shape, and comprises a body, 18, upper flanges, 19, and lower flanges, 20. The lateral width of the flanges is such that the key may be inserted through the notches, 13, and moved to the position shown in Figs. 2 and 3, with the flanges, 20, underlying the metal of the tie adjacent to the slot. The body portion, 18, of the retainer will occupy the space between the bifurcations of the clamp and the flanges, 19 will overlie the said bifurcations.

The holding device comprises a resilient wedge key shown in detail in Figs. 6 and 7, consisting of a body portion, 21, that is reduced in cross section at 22, a pair of arms, 23 and a head having inclined surfaces or faces, 24, the inclination of which will preferably correspond to that of the surface 17, on the clamp. The arms, 23, extend past the body of the retainer and as the under-surfaces of the arms are inclined corresponding to the upward inclination of the upper surfaces of the bifurcations, 14, of the clamp, the key will, when driven into the position shown in Fig. 2, act as a positive wedge or retaining key for the retainer. The body

portion, 21, of the wedge prevents the backward movement of the retainer toward the only outlet or escape for the retainer, that is, the notches, 13. Preferably the wedge is composed of resilient metal and the reduced cross section at 22, permits the key to bend sufficiently to enable it to be driven into position with the surfaces, 17, 24, in contact. The angle of such surfaces will be such that if occasion requires, the wedge 10 may be driven backward out of the holding position by means of a drift pin, 25, such as shown in dotted lines, in Fig. 2.

It will be noted that vertical thrust exerted by the rail on the parts constituting the clamp is likewise resisted by positive elements and that actual distortion of the retainer is necessary before such thrusts would be effective to permit escape of the rail. While I have shown and described the key as composed of resilient material, it 20 will be understood that a simple wedge might be employed and distorted as required to hold it in position.

25 An important and fundamental advantage in the construction described is that of the positiveness of the engagement between the parts. There is no possibility of loosening or disengagement under any conditions 30 short of the actual destruction of the clamping element. Notwithstanding this advantage of firm engagement, the parts may very readily be disengaged by applying a lateral wedging force exerted on the wedge key, 35 the force necessary to effect disengagement being applied at a point where there is no stress applied in normal operation.

I claim:

40 1. In a rail holding device, the combination with a hollow tie, having a longitudinal slot in its upper wall and a lateral recess in communication with said slot, of a clamp having a head adapted to overlie the rail base, a body lying alongside of the slot and a toe entering the lateral recess, a 45 retainer having a portion overlying the body of the clamp and a portion entering the slot and underlying the margin thereof, and a wedge adapted to be driven between the top 50 surface of the body and the overlying portion of the retainer.

55 2. In a rail holding device, the combination with a hollow tie having a longitudinal slot in its upper wall, and a lateral recess in communication with said slot, of a clamp having a head adapted to overlie the rail base, a body lying alongside of the slot and a toe entering the lateral recess, a retainer having a portion overlying the body of the 60 clamp and a portion entering the slot and underlying the margin thereof, and a resilient wedge adapted to be driven between the top surface of the body and the overlying portion of the retainer.

65 3. In means of the class described, the

combination of a hollow tie, having a slot in its upper surface and a recess opening into the slot, a rail clamp having a head adapted to overlie a rail base, a body adapted to lie alongside of said slot and a toe having a portion adapted to enter said recess and a stop portion extending above the plane of the body, a retainer having a portion underlying the walls of the tie and a portion overlying the body of the clamp, and a wedge adapted to be driven between the body and overlying portion of the retainer and be held against reverse movement by said stop portion.

4. In means of the class described, the 80 combination of a hollow tie, having a slot in its upper surface and a recess opening into the slot, a rail clamp having a head adapted to overlie a rail base, a body adapted to lie alongside of said slot and a toe having a portion adapted to enter said recess and a stop portion extending above the plane of the body, a retainer having a portion underlying the walls of the tie and a portion overlying the body of the clamp, 85 and a resilient wedge adapted to be driven between the body and overlying portion of the retainer and be held against reverse movement by said stop portion.

5. In means of the class described, the 95 combination of a hollow tie, having a slot in its upper surface and a recess opening into the slot, a rail clamp having a head adapted to overlie a rail base, a body adapted to lie alongside of said slot and a toe 100 having a portion adapted to enter said recess and a stop portion extending above the plane of the body, a retainer having a portion underlying the walls of the tie and a portion overlying the body of the clamp, 105 a resilient wedge adapted to be driven between the body and overlying portion of the retainer and be held against reverse movement by said stop portion and positive means on said wedge preventing horizontal 110 movement of said retainer.

6. In a rail holding device, the combination of a tie having a recess in its top surface, a clamp having portions abutting against and overlying a rail base, and a 115 portion entering said recess and abutting against a wall thereof, whereby lateral thrust of the rail is positively resisted, a retainer overlying said clamp and entering said recess and underlying a wall thereof 120 and a wedge driven between the clamp and the retainer and positioned by distortion of the said wedge whereby vertical thrust exerted on said clamp is positively resisted.

7. In means of the class described, the 125 combination with a hollow tie having a slot in its upper surface, and lateral notches in communication with the slot, of a rail clamp having a bifurcated body, a head adapted to overlie a rail base, and a toe on each bifur- 130

cation adapted to enter the notches, an I-shaped retainer, the lower flanges of which are adapted to underlie the walls adjacent to the slot in the tie and the upper walls of which overlie the bifurcations of the body and a wedge having a pair of tongues adapted to be driven between the body portions

and the overlying portions of the retainer, the body of the wedge preventing horizontal movement of the retainer in reverse direction. 10

In testimony whereof I have affixed my signature.

- CHARLES P. KIMMEL.
